Primary Examiner — Raphael Barkai*Assistant Examiner* — Randall Gholson*(74) Attorney, Agent, or Firm* — Maier & Maier PLLC(57) **CLAIM**

The ornamental design for a knee and shin protector, as shown and described.

DESCRIPTION

FIG. 1 is a front perspective view of a knee and shin protector, showing my design;

FIG. 2 is a front view thereof;

FIG. 3 is a rear view thereof;

FIG. 4 is a right side view thereof, the left side view being a mirror image of the right side view;

FIG. 5 is a top view thereof;

FIG. 6 is a bottom view thereof;

FIG. 7 is a front view of the knee portion of the knee and shin protector of FIG. 1;

FIG. 8 is a rear view thereof;

FIG. 9 is a right side view thereof, the left side view being a mirror image of the right side view;

FIG. 10 is a top view thereof;

FIG. 11 is a bottom view thereof;

FIG. 12 is a front view of the shin portion of the knee and shin protector of FIG. 1;

FIG. 13 is a rear view thereof;

FIG. 14 is a right side view thereof, the left side view being a mirror image of the right side view;

FIG. 15 is a top view thereof; and,

FIG. 16 is a bottom view thereof.
